The ornamental design for a resilient doorstop, as shown and described.

DESCRIPTION

FIG. 1 is a front, top and right side perspective view of a resilient doorstop embodying my new design;

FIG. 2 is a front, top and left side perspective view thereof;

FIG. 3 is a reduced front end elevational view thereof;

FIG. 4 is a reduced rear end elevational view thereof;

FIG. 5 is a reduced left side elevational view thereof, the right side being a mirror image;

FIG. 6 is a reduced top plan view thereof;

FIG. 7 is a reduced bottom plan view thereof;

FIG. 8 is a perspective view identical to FIG. 1, the portion of a door being shown in broken lines for illustrative purposes only;

FIG. 9 is a front end elevational view identical to FIG. 3, the portions of a door and floor being shown in broken lines for illustrative purposes only; and,

FIG. 10 is a further reduced rear perspective view thereof, the portions of a door, frame, wall and floor being shown in broken lines for illustrative purposes only.

FIG. 1
